UNITED STATES PATENT OFFICE.

CHARLES D. HAVENS, OF FAIRFAX, OKLAHOMA.

CLEVIS.

1,095,859.

Specification of Letters Patent.

Patented May 5, 1914.

Application filed November 26, 1913. Serial No. 803,344.

To all whom it may concern:

Be it known that I, CHARLES D. HAVENS, a citizen of the United States, residing at Fairfax, in the county of Osage and State 5 of Oklahoma, have invented certain new and useful Improvements in Clevises, of which the following is a specification, reference being had to the accompanying drawings.

This invention relates to new and useful 10 improvements in clevises in connection with vehicle tongues and poles and the primary object of the invention is to provide an improved clevis in which means is provided for the retention of the pivot pin or bolt in 15 place.

A further object of the invention resides 20 in providing a clevis which is so constructed as to avoid the interference in the operation of the swingle-tree or double-tree and which 25 will not become unduly worn in ordinary usage.

Still another object of the invention resides 25 in providing a device which is simple and durable in construction, inexpensive to man- 30 ufacture and one which will be very efficient and useful in operation.

With these and other objects in view, the 35 invention consists in the novel features of construction, combination and arrangement 40 of parts as will be hereinafter referred to and more particularly pointed out in the specification and claims.

In the accompanying drawing forming a 45 part of this application, Figure 1 is an ele- 50 vation of a clevis constructed in accordance 55 with my invention. Fig. 2 is a plan view 60 thereof with the bolt removed. Fig. 3 is a fragmentary vertical section therethrough; 65 and Fig. 4 is a fragmentary bottom plan 70 view of the device.

In describing my invention, I shall refer 75 to the drawing in which similar reference 80 characters designate corresponding parts 85 throughout the several views and in which 90 1 indicates the body of a clevis of the usual U- 95 shaped design, the free ends of the arms of 100 which are provided with the alining open- 105 ings 2. A pivot pin or bolt 3 is designed for 110 introduction through the alining openings 2, 5 said bolt having a head 4 thereon which is 115 adapted to be partially received in a recess 120 or counter-sunk portion 5 in the outer face 125 of the one arm of said body. The outer face 130 of the head 4 projects slightly beyond the 135 outer face of the referred to arm of said 140 body and the outer face of the opposite arm

adjacent the opening therein is bossed on 145 both sides thereof, as shown at 6 to partially 150 inclose the outer projecting end of the bolt 155 3. The bosses 6 are beveled so that any 160 member contacting therewith will ride 165 thereover and be prevented from engagement 170 with the outer or free end of said bolt 175 and these bosses on opposite sides of the 180 opening in the arm of the body are so de- 185 signed as to admit of the finger of the operator 190 to be received therebetween to force the 195 bolt upwardly through the openings in the 200 arms when it is desired to remove the bolt. 205 It will be seen that in this construction no 210 means is provided in connection with the 215 free end of the bolt for the retention of the 220 latter in place, it being an object of this 225 invention to eliminate such means in view of 230 the inconveniences and difficulties heretofore 235 experienced in the use of the same. It is a 240 well known fact that the use of cotter pins, 245 nuts and other engaging means in a clevis 250 affords a means whereby the latter may 255 become unduly worn and readily engage with 260 other members with which the clevis in use 265 might contact. I, therefore, provide an im- 270 proved means for the retention of the bolt 275 in place which consists of a plate-like mem- 280 ber 7 which is pivotally secured on a rivet 285 or pin 8 in the arm of the body in which the 290 recess 5 is provided. The pivoted end of the 295 plate-like member 7 is reduced somewhat 300 and the main or body portion of the plate is 305 bulged outwardly or recessed, as shown at 9, 310 to readily receive therein the projecting por- 315 tion of the head 4 of said bolt 3. This plate 320 member 7 is formed of spring metal and is 325 adapted to be forced in place over the pro- 330 jecting portion of the head of the bolt, in 335 the application of the plate member to its 340 effective position and it must be here stated 345 that this plate member is of such construc- 350 tion as to conform to the contour or outline 355 of the one end of the arm of the body of the 360 clevis.

When the plate-like member 7 has been 365 forced into effective position over the head 370 of the bolt, the projecting portion of the 375 head of the bolt will be received in the 380 bulged portion of the plate-like head mem- 385 ber, although the head of the bolt itself 390 will not positively contact with the wall 395 of said bulged portion, inasmuch as it is 400 a feature of the invention to avoid such con- 405 tact during the use of the device. By per- 410 mitting the inner wall of the bulged por-

tion of the plate-like member to avoid contact with the head of the bolt, any corrosion of the metal will not prevent the ready operation of said plate member.

5 In order to lock the plate member in its effective position, when so disposed, inwardly extending lugs 10 are formed adjacent the outer edge of the plate member on opposite sides thereof. These lugs are
 10 adapted to fit in slight recesses or notches
 11 formed in or attached to the particular arm to which said plate member is applied. It will, of course, be understood that this plate member is slightly loose on its
 15 pivot, in order to admit of the same being removed from the arm of the body of the clevis. The same being of spring metal, however, will admit of the same being applied or removed, with but a slight loose
 20 movement at the pivot point thereof. This spring plate member 7 may be said to form a cap for the head of the bolt, for the retention of the latter in place and when said cap is disposed to its operative position over
 25 the head of the bolt, it will be seen that the same is seated closely against the upper side of the upper arm of the clevis and avoids any possibility of the same being accidentally displaced. It will also be seen that the cap
 30 member is formed of a single piece of metal and has no lateral projections which are liable to contact with members coming in contact with the clevis during the operation of the device. It will also be seen that the
 35 bossed portions 6 on the lower arm of the clevis will protect the lower projecting portion of the bolt and prevent the latter from being raised, while the cap is in proper position and also permit the clevis to be
 40 readily passed over any surface, without contacting with said bolt.

It will also be seen that this device is simple and durable in construction, inex-

pensive to manufacture and one which will be very efficient and useful in operation. 45

While I have particularly described the elements best adapted to perform the functions set forth, it is obvious that various changes in form, proportion and in the minor details of construction may be resorted to without departing from the spirit or sacrificing any of the principles of the invention. 50

Having thus described this invention, what I claim is:— 55

1. A clevis of the class described comprising a U-shaped body having openings in the arms thereof, a bolt introduced through said openings, a spring cap member pivotally carried on the one arm of said body to 60 cover the head of said bolt and retain the latter in place in the body, and lugs formed on the outer end of said cap member adapted for engagement with portions of the body to retain said cap member in place thereon. 65

2. A clevis of the class described comprising a U-shaped body having alining openings in the arms thereof, one arm of said body being also provided with notches adjacent the free end thereof, a bolt introduced through said alining openings, a spring cap member pivotally carried on the last mentioned arm of the body and designed to cover the head of the bolt to retain the latter in place in said body, and integral lugs formed on said cap member adapted to be received in the notches of the arm of said body to retain said cap member in its operative position on said body. 70 75

In testimony whereof I hereunto affix my 80 signature in the presence of two witnesses.

CHARLES D. HAVENS.
